UNITED STATES PATENT OFFICE.

WILLIAM BEST, OF MORLEY, ENGLAND, ASSIGNOR TO THE ACKROYD & BEST, LIMITED, OF SAME PLACE.

APPARATUS FOR ELECTRICALLY IGNITING MINERS' SAFETY-LAMPS.

SPECIFICATION forming part of Letters Patent No. 625,014, dated May 16, 1899.

Application filed December 23, 1897. Serial No. 663,120. (No model.)

To all whom it may concern:

Be it known that I, WILLIAM BEST, a subject of the Queen of Great Britain and Ireland, and a resident of Morley, near Leeds, 5 in the county of York, England, have invented certain new and useful Improvements in Apparatus for Electrically Igniting Miners' Safety-Lamps, (for which I have obtained a patent in Great Britain, No. 4,082, bearing 10 date February 22, 1896,) of which the following is a specification.

This invention refers to apparatus for electrically igniting miners' safety-lamps; and the object is to construct apparatus whereby 15 the wicks of the said lamps may be ignited in a more expeditious and certain manner than heretofore.

In order that my invention may be clearly understood, I will proceed to describe the same 20 with reference to the accompanying drawings, in which similar letters refer to like parts in both figures.

Figure 1 is a vertical section of a lamp constructed according to my invention, and Fig. 25 2 is a section of an apparatus for electrically igniting the said lamp.

A is a conductor provided with a cap A', which conductor passes through the center of the wick B by way of an insulating-tube C, 30 and the said tube C is held in position by a tube D, which latter is securely fixed to the lamp-bottom E.

F is the wick-tube, which holds the wick at the required height, and G is a regulating- 35 tube which slides on the wick-tube F, and the height of the regulating-tube G may be regulated by a screw H, thus enabling the flame from the wick to be raised or lowered, as desired.

40 Referring particularly to Fig. 2, J is a wire which connects a battery K with a terminal L of a coil M, and N is a wire which connects the other terminal P of the coil M with the said battery K, a push-switch R being provided for connecting and disconnecting the 45 battery. S is a ring for the reception of the

lamp to be lighted, and the push-switch R comes through the ring S, so as to be actuated by the lamp on the latter being inserted in the said ring. T is a spring-contact which 50 is connected with the secondary circuit of the coil M by means of wire U, and V is another contact-piece, which is connected to the other pole of the secondary circuit of the coil M by means of a wire W. 55

By placing a lamp constructed as described with reference to Fig. 1 in the ring S the spring-contact T comes against the conductor A and the edge of the lamp-bottom E rests on the contact-piece V, thus completing 60 the secondary circuit of the coil M. The placing of the lamp in the ring S depresses the push-switch R, thereby connecting the coil M with the battery K, and this connection causes an induced current to pass from the 65 coil M through the wire U, spring-contact T, and the conductor A, from which latter it passes in the form of a spark or sparks across the wick B to the regulating-tube G, and thence by way of the lamp-bottom E, contact-piece V, and wire W back to the coil M. The sparks in passing between the cap A' and regulating-tube G ignite the wick B, and the central position of the conductor A enables the said sparks to pass directly over and in 70 contact with the said wick, thus obviating the danger hitherto experienced of the electric sparks failing to come in contact with the wick and therefore failing to light the same. 75

Having now described my invention, what 80 I claim as new, and desire to secure by Letters Patent, is—

1. A miner's lamp having a metallic base, a wick and means for adjusting the same, a central conductor A and means for insulating the same, in combination with a ring for receiving the base of the lamp, a central spring-contact, an induction-coil and connections therefrom to the central contact and to a contact for the lamp-base, a push-switch actuated by the lamp for closing an electric circuit to the primary of the induction-coil so 85 90

that the spark from the induction-coil is directed across the wick to the metal of the lamp, substantially as specified.

2. A miner's lamp having a tubular wick B carried on a tube D securely attached to the lamp-bottom E, and an adjustable wick-tube G, in combination with a central conductor A insulated from the lamp-bottom by an in-

sulating-tube C and carrying a cap A', together with a suitable apparatus for passing a current from the cap A' across the wick B to the wick-tube D, substantially as set forth.

WILLIAM BEST.
